ARTICLE DISPENSING CONTAINER

Harry Crane, Philadelphia, Pa.

Application January 22, 1944, Serial No. 519,283

2 Claims. (Cl. 229—7)

This invention relates to an improved construction of a container designed for dispensing therefrom the articles contained therein, the present container being particularly adapted for dispensing tablets and the like one at a time as needed or desired.

Among the principal objects of the present invention is to provide such a container which in outward appearance is similar to that of conventional packages now in use, which is adapted to be manufactured entirely of paper or other such material of which the conventional packages are now being made and which is simple in design and economical of manufacture.

Other objects and advantages of the invention will appear more fully hereinafter, it being understood that the present invention consists in the combination, construction, location and relative arrangement of parts, all as will appear more fully from the detailed description which follows, as shown in the accompanying drawings and as finally pointed out in the appended claims.

In the accompanying drawing,

Figure 1 is a perspective view of the container of the present invention, a part of which is broken away to show the interior of the container when the same is in closed condition;

Figure 2 is a similar view showing the inner part of the container extended into article-dispensing position;

Figure 3 is a view corresponding to Figure 1 showing the front portion of the container in closed condition;

Figure 4 is a view corresponding to Figure 2 showing the inner part of the container extended into dispensing position;

Figure 5 is a perspective view of the inner movable part of the container;

Figure 6 is a plan view of the blank from which the movable part is formed;

Figure 7 is a sectional view taken on the line 7—7 of Figure 3; and

Figure 8 is a sectional view taken on the line 8—8 of Figure 3.

Referring now more particularly to the drawing, it will be observed that the container of the present invention comprises two main parts consisting respectively of an outer shell 10 and an inner member 10^a. The outer shell 10, is preferable formed of a single blank of suitable sheet material, such as paper, cardboard, or the like, which is suitably cut, scored and folded to provide a box of conventional construction having a top 11, a bottom 12, opposite side walls 13 and 14, a closed rear wall 15 and a front end closure wall 16 having the conventional tab 17, which is insertable interiorly of the box 10 when the same is closed. It will be noted, however, that in the present construction, this front end wall 16

extends only partially across the full width of the box 10 to close preferably only one-half of the front opening thereof, as most clearly appears in Figures 1, 3 and 4.

5 The other member 10^a of the container of the present invention is formed of a single blank of similar sheet material which is cut to shape and scored as shown most clearly in Figure 6, the main body 18 of this blank being of a width 10 adapted to fit snugly within the interior of the outer shell or box 10 so as to provide for the latter a longitudinally shiftable bottom upon the upper surface of which is disposed the several tablets or the like which are to be dispensed from the container. This blank of which the member 10^a is formed is provided at one end thereof with an extension 19 which is scored along the dotted lines 20, 21 and 22, and cut along the lines 23 and 24 to provide a series of 15 flap elements 25, 26 and 27 which are adapted to be bent upwardly and secured together, as shown more particularly in Figure 5, to provide the inner member 10^a at the forward end thereof with a three-sided pocket member 28. This pocket member 28 is of a depth approximately equal to the internal height of the main outer shell or box 10, while the overall length of the member 10^a, including the pocket member 28 thereof, approximately equals the overall length of said main box. The width of the pocket member 28 20 approximately equals the width of the open part of the front end of the box 10, from which it will appear that when the said member 10^a is inserted within the box 10 and moved to its rear-most position therein, as shown in Figures 1 and 3, the front end wall of the pocket member 28 serves conjointly with the front member 16 of the box 10 to completely close the front end of the box.

25 The articles to be dispensed are normally packed in the box in a single layer and in two rows extending from the front to the rear ends of the closed container, in consequence of which it will be understood that one of said articles will 30 occupy the pocket 28 when the container is completely filled. In order to dispense these articles from the container one at a time, it is merely necessary to withdraw the member 10^a from the main outer shell 10 to an extent sufficient to 35 fully expose the pocket member part 28 of the member 10^a, as shown in Figure 4. To facilitate so withdrawing the member 10^a into the article dispensing position shown in Figure 4, the top wall 11 of the shell may be cut away, as at 29, 40 to provide an opening 30 immediately adjacent the upper edge of the front wall 27 of the compartment 28 to facilitate grasping said front wall 27 by the fingers and so withdrawing the inner member into its article dispensing position. It 45 will be understood, of course, that the edge 31 of

the inner member 10^a engages the closed front wall 16 of the shell 10 to limit the extent to which the member 10^a may be withdrawn from its enclosing outer body or shell 10.

Having dispensed the first article originally deposited in the compartment 28, it will be obvious that the remaining articles packed in the container may be successively dispensed therefrom one at a time by the simple expedient of shifting the member 10^a into its rearmost position and then inclining the container 10 in such manner as to cause one of the articles contained therein to move into the compartment 28 whereupon such article may be dispensed from the container when the member 10^a is shifted longitudinally of the shell 10 into the position shown in Figures 2 and 4.

To further facilitate the ready removal of an article from the compartment 28 when the same is outwardly drawn into its dispensing position, the member 10^a may be scored along the line 32 to thereby permit the pocketed extension 28 thereof to be bent downwardly out of its normal plane into the dotted line position as shown in Figure 4.

It will be understood, of course, that the present invention is susceptible of various changes and modifications which may be made from time to time without departing from the general prin-

ciples or real spirit thereof, and it is accordingly intended to claim the same broadly, as well as specifically, as indicated by the appended claims.

What is claimed as new and useful is:

- 5 1. In an article-dispensing package of the character described, a main outer box or shell for receiving therein the articles to be dispensed, said box being provided with an opening extending partially across the width of one end thereof, and a slidable member disposed interiorly of said box and having a three-walled pocket formed at one end thereof, the mouth of said pocket presenting interiorly of the box and the closed end of the pocket being normally positioned in the plane of the opening in the end of the box to completely close the latter against displacement of the contents from the box.
- 10 2. In an article-dispensing package as defined in claim 1 wherein said slidable member is adapted to be shifted longitudinally of the box to present said pocket in outwardly extended relation with respect to the box and with said mouth of the pocket substantially coincident with the opening aforesaid in the end of the box, the pocket being thus adapted to receive from within the interior of the box one of the articles to be dispensed.
